UNITED STATES PATENT OFFICE.

JAMES K. DIAMOND, OF GRAND RAPIDS, MICHIGAN, ASSIGNOR TO CLIPPER BELT LACER COMPANY, OF GRAND RAPIDS, MICHIGAN.

MACHINE FOR APPLYING BELT FASTENERS AND THE LIKE.

Application filed June 6, 1927. Serial No. 196,946.

My present improvements are an adaptation and in some respects an improvement upon the machine for applying belt fasteners and the like illustrated and described in my application for Letters Patent, Serial No. 105,424, filed April 29, 1923.

The main objects of this invention are:

First, to provide an improved means for supporting the fastener holder in operative relation to the jaws.

Second, to provide an improved adjusting means for the jaw supports whereby they may be accurately adjusted, their relation to each other being maintained throughout the adjustment.

Objects relating to details and economies of construction and operation of my invention will definitely appear from the detailed description to follow.

The invention is defined and pointed out in the claims.

A structure which is a preferred embodiment of my invention is illustrated in the accompanying drawing, forming a part of this application, in which:

Fig. 1 is a side elevation of a machine embodying the features of my invention.

Fig. 2 is a detail view mainly in horizontal section on a line corresponding to line 2-2 of Figs. 1, 3, 4 and 6.

Fig. 3 is a fragmentary view mainly in vertical section on a line corresponding to line 3-3 of Figs. 1, 2 and 4.

Fig. 4 is a fragmentary view partially in longitudinal section on a line corresponding to line 4-4 of Figs. 2 and 3.

Fig. 5 is an enlarged detail vertical longitudinal section showing details of the fastener holder and the relation of the fasteners and work thereto.

Fig. 6 is a detail section on line 6-6 of Fig. 2.

In the drawing similar reference characters refer to similar parts throughout the several views, and the sectional views are taken looking in the direction of the little arrows at the ends of the section lines.

Referring to the drawings, the supporting bed or base is conventionally indicated at 1.

On this is mounted the base brackets 2 which carry the base rod 3. These base rods have

nuts 4 threaded upon each end thereof. Centrally of these rods I mount a pair of uprights 5 having opposed vertical ways 6 in their inner sides, their upper ends being vertically slotted at 7 to receive the threaded bushings 8.

The base rods also carry jaw supports 9 which are arranged in opposed pairs, these jaw supports being tiltingly mounted on the base rods as is described in my said application for Letters Patent.

The jaw supports are adjusted and supported in their adjusted position by means of the rods 10 which are arranged in the horizontal aligned bores 11 in the supports, the bores being of such size as to permit a swinging movement of the supports.

The rods are arranged through cross bars 12 and 13 disposed at the outer ends of the supports, the rods having threaded portions 14 at the centers thereof engaging the threaded bushings 8 in the upper ends of the uprights.

The rods are also threaded at 15 to receive the adjusting nuts 16 which are held against rotation by the locking bar 17, the nuts having serrated peripheral portions 18, the bar having holes 19 correspondingly serrated to engage the nuts. At the outside of the serrations the nuts have annular grooves 20 which are engaged by the split rings 21 for retaining the locking bar on the nuts. At their opposite ends the rods are provided with adjusting sprockets 22 connected by sprocket chain 23, one of the sprockets having a crank 24 so that the rods may be simultaneously adjusted.

Coiled springs 25 are arranged between the uprights and fasteners to urge the jaw supports yieldingly outward.

By providing threaded engagement of the rods with the uprights of a pitch half that of the threads at the outer ends of the rods, the supports are kept properly centered relative to the uprights.

Each of the jaw supports is provided with a flat thrust bearing plate 26 against which the jaws 26 are rockingly supported. These jaws are provided with downwardly projecting arms 27. The jaws are supported with their bearings in proper relation to the

thrust bearing of the supports by means of holders 28 having segmental slots 29 therein engaged by pins 30 on the jaw arms. This means of supporting the jaws may be that described in my said application for Letters Patent.

As in my said application for Letters Patent, the jaws are actuated by a pinion 31 mounted on the uprights and coacting with a rack 32 to the upper end of which the arms 27 of the jaws are connected by the links 33. The links are connected to a cross member 34 projecting from the rack and engaging the ways in the uprights.

15 The jaws are provided with jaw faces 35 above the plane of their axial centers and with rectangular slot-like recesses 36 below these jaw faces.

The fastener holder 37 is of general T-shape and is provided with a series of transverse slots 38 adapted to receive a series of the fasteners 39, the fasteners being retained in the holder by a longitudinal pin 40.

The fastener holder has curved bearing portions 41 on the lower sides of its arms and curved bearing portions 42 on the upper sides thereof, these bearing portions being arcs of the same circle and engaging the bottoms and tops respectively of the recesses 36 in the jaws, so that as the jaws rock on their supports, the fastener holder is always maintained in the same relation relative to the faces of the jaws.

To properly center the fastener holder, I provide a pair of plunger-like centering members 43 which are mounted for vertical movement in the vertical bores 44 in the uprights 5, coiled springs 45 acting to urge these centering members yieldingly upward.

40 The retaining clips 46 are mounted on the uprights 5 to engage flattened portions 47 on the members 43, the shoulders 48 at the bases of these flattened portions constituting stops limiting the upward movement of the centering members at their upper ends.

45 The centering members are provided with projecting lugs 49 which engage slots 50 in the fastener holder. Through one of these slots, I arrange a pair of spacing pins 51 by means of which the holder may be longitudinally positioned.

With the parts thus arranged, the hooks are supported as they are forced into the work indicated at 52 in such a manner that the desired curvature at the bight is maintained on all of the hooks. Further, the prongs are set at predetermined angles in the work so that a maximum of pulling strength is secured without cutting or tearing the belt.

60 I have illustrated and described my improvements in an embodiment which I have found very satisfactory in practical use. I have not attempted to illustrate or describe certain modifications or adaptations which 65 I contemplate as I believe this disclosure

will enable those skilled in the art to embody or adapt my improvements as may be desired.

Having thus described my invention, what I claim as new and desire to secure by Letters Patent, is:

1. In a structure of the class described, the combination of opposed jaw supports provided with opposed thrust bearings, jaws provided with curved bearings coacting with said thrust bearings of said jaw supports, said jaws having jaw faces above the planes of their axial centers and opposed recesses of rectangular cross section disposed below their said jaw faces, a fastener holder disposed between said jaws with its edges projecting into said recesses, said holder having curved bearing surfaces at the top and bottom thereof in bearing engagement with the top and bottom respectively of said recesses, a pair of vertically reciprocating yieldingly supported centering members disposed below said fastener holder, said fastener holder being provided at one end with longitudinal positioning means engageable with one of said centering members, and means for actuating said jaws.

2. In a structure of the class described, the combination of opposed jaw supports provided with opposed thrust bearings, jaws provided with curved bearings coacting with said thrust bearings of said jaw supports, said jaws having jaw faces above the planes of their axial centers and opposed recesses of rectangular cross section disposed below their said jaw faces, a fastener holder disposed between said jaws with its edges projecting into said recesses, said holder having curved bearing surfaces at the top and bottom thereof in bearing engagement with the top and bottom respectively of said recesses, a pair of vertically reciprocating yieldingly supported centering members disposed below said fastener holder, said fastener holder being provided at one end with longitudinal positioning means engageable with one of said centering members, and means for actuating said jaws.

3. In a structure of the class described, the combination of opposed jaw supports provided with opposed thrust bearings, jaws provided with curved bearings coacting with said thrust bearings of said jaw supports, said jaws having faces above the planes of their axial centers and opposed recesses, a fastener holder disposed between said jaws with its edges projecting into said recesses, a pair of vertically reciprocating yieldingly supported centering members disposed below said fastener holder, said fastener holder being provided at one end with longitudinal positioning means engageable with one of said centering members, and means for actuating said jaws.

4. In a structure of the class described, the combination of opposed jaw supports provided with opposed thrust bearings, jaws provided with curved bearings coacting with

said thrust bearings of said jaw supports, said jaws having jaw faces above the planes of their axial centers and opposed recesses, a fastener holder disposed between said jaws with its edges projecting into said recesses, a pair of vertically reciprocating yieldingly supported centering members disposed below said fastener holder, and means for actuating said jaws.

10 5. In a structure of the class described, the combination of opposed jaw supports mounted for adjustment to and from each other and provided with opposed flat thrust bearings; jaws provided with curved bearings mounted to coact with said thrust bearings of said jaw supports, said jaws being provided with jaw faces above the axial center thereof and with opposed longitudinal recesses below their said faces, a fastener holder removably engageable with said recesses, and vertically reciprocating yieldingly supported centering members with which said fastener holder is removably engaged.

6. In a structure of the class described, the combination of rockingly mounted jaws provided with jaw faces above the axial centers thereof and with opposed longitudinal recesses below their said faces, a fastener holder removably engageable with said recesses, and vertically reciprocating yieldingly supported centering members with which said fastener holder is removably engaged.

7. In a structure of the class described, the combination of opposed jaw supports, jaws rockingly mounted on said supports and having flat jaw faces above the plane of their axial centers and opposed recesses below their jaw faces, a fastener holder engaged in said recesses, and a fastener holder positioning member disposed between said jaws to coact with the holder when the same is engaged with the said recesses.

8. In a structure of the class described, the combination of rockingly mounted jaws having flat jaw faces above the plane of their axial centers and opposed fastener holder engaging parts below their jaw faces, a fastener holder, and a fastener holder positioning member coacting with the holder when the same is engaged with the said jaws.

9. In a structure of the class described, the combination of opposed jaw supports mounted for adjustment to and from each other and provided with opposed thrust bearings, jaws rockingly supported to coact with said thrust bearings of said jaw supports and provided with opposed fastener holder engaging parts, a fastener holder, and a yieldingly supported fastener holder centering means disposed to coact with the fastener holder while the same is engaged with said jaws.

10. In a structure of the class described, the combination of rockingly supported jaws

provided with fastener holder engaging parts, a fastener holder engaging said jaws, and a yielding fastener holder centering means coacting with the fastener holder while the same is engaged with said jaws. 70

11. In a structure of the class described, the combination of rockingly supported jaws provided with fastener holder engaging parts, a fastener holder engaging said jaws, and a fastener holder centering means co- 75 acting with the fastener holder while the same is engaged with said jaws.

12. In a structure of the class described, the combination of spaced horizontally disposed base bars, uprights disposed centrally 80 on said base bars and provided with threaded bushings at their upper ends and with opposed inwardly facing ways, opposed pairs of jaw supports mounted on said bars for adjustment to and from each other, rods 85 for adjustably supporting said jaws having threaded engagement with said bushings in said uprights, said rods having sprockets on one end thereof and being threaded at their outer ends, the pitch of the threads engaging 90 the said bushings being one-half that at the ends of the rods, a connecting chain for said sprockets whereby the rods are simultaneously rotated, adjusting nuts on the threaded ends of said rods, springs arranged on said rods 95 between said uprights and said jaw supports acting to hold said jaw supports yieldingly outward, jaws rockingly mounted on said jaw supports and provided with downwardly projecting arms disposed between 100 said jaw supports, a rack provided with guide members coacting with said ways of said uprights, links connecting the upper ends of said rack to the lower ends of said jaw arms providing an actuating toggle for 105 said jaws, and a driving pinion mounted on said uprights to coact with said rack.

13. In a structure of the class described, the combination of spaced horizontally disposed base bars, uprights disposed centrally 110 on said base bars and provided with threaded bushings at their upper ends, opposed pairs of jaw supports mounted on said bars for adjustment to and from each other, rods for adjustably supporting said jaws 115 having threaded engagement with said bushings in said uprights, said rods having sprockets on one end thereof and being threaded at their other ends, the pitch of the threads engaging the said bushings being 120 one-half that at the ends of the rods, a connecting chain for said sprockets whereby the rods are simultaneously rotated, adjusting nuts on the threaded ends of said rods, springs arranged on said rods between said 125 uprights and said jaw supports acting to hold said jaw supports yieldingly outward,

jaws rockingly mounted on said jaw supports, and means for actuating said jaws.

14. In a structure of the class described, 130

the combination of spaced horizontally disposed base bars, uprights disposed centrally on said base bars and provided with threaded bushings at their upper ends, opposed pairs 5 of jaw supports mounted on said bars for adjustment to and from each other, rods for adjustably supporting said jaws having threaded engagement with said bushings in said uprights, said rods having sprockets on 10 one end thereof and being threaded at their other ends, the pitch of the threads engaging the said bushings being one-half that at the ends of the rods, a connecting chain for said sprockets whereby the rods are simultaneously rotated, adjusting nuts on the threaded ends of said rods, jaws rockingly mounted 15 on said jaw supports, and means for actuating said jaws.

15. In a structure of the class described, 20 the combination of opposed jaw supports mounted for adjustment to and from each other, uprights disposed centrally between said jaw supports, rods for adjustably supporting said jaw supports having threaded 25 engagement with said uprights, said rods being threaded at one end, the pitch of the threads engaging the said uprights being one-half that at the ends of the rods, means for simultaneously rotating said rods, nuts 30 on the threaded ends of said rods, springs arranged on said rods between said uprights and said jaw supports coacting to hold said jaw supports yieldingly outward, jaws mounted on said jaw supports, and means 35 for simultaneously actuating said jaws.

16. In a structure of the class described, the combination of opposed jaw supports mounted for adjustment to and from each other, uprights disposed centrally between 40 said jaw supports, rods for adjustably supporting said jaw supports having threaded engagement with said uprights, said rods being threaded at one end, the pitch of the threads engaging the said uprights being one-half that at the ends of the rods, means 45 for simultaneously rotating said rods, nuts on the threaded ends of said rods, jaws mounted on said jaw supports, and means for simultaneously actuating said jaws.

50 17. In a structure of the class described, the combination of opposed jaw supports mounted for adjustment to and from each other, uprights disposed centrally between said jaw supports, rods for adjustably supporting said jaw supports having threaded engagement with said uprights, said rods being threaded at one end, the pitch of the threads engaging the said uprights being one-half that at the ends of the rods, means 55 for simultaneously rotating said rods, nuts on the threaded ends of said rods provided with serrated peripheral portions, a locking bar common to both of said nuts provided with serrated openings coacting with said serrations of said nuts, jaws mounted on said 60

jaw supports, and means for simultaneously actuating said jaws.

18. In a structure of the class described, the combination of opposed pairs of jaw supports mounted for adjustment to and from 70 each other, uprights disposed centrally between said jaw supports, rods for adjustably supporting said jaw supports having threaded engagement with said uprights, means for simultaneously rotating said rods, nuts on the threaded ends of said rods provided with serrated peripheral portions, a locking bar common to both of said nuts provided with serrated openings coacting with said serrations of said nuts, said nuts having peripheral grooves at the outer side of said locking bar, split rings engaging said grooves for retaining said locking bar in engagement with said nuts, jaws mounted on said jaw supports, and means for actuating said jaws. 80

19. In a structure of the class described, the combination of opposed pairs of jaw supports mounted for adjustment to and from each other, uprights disposed centrally between said jaw supports, rods for adjustably 90 supporting said jaw supports having threaded engagement with said uprights, means for simultaneously rotating said rods, nuts on the threaded ends of said rods, jaws mounted on said jaw supports, and means for actuating said jaws.

20. In a structure of the class described, the combination of opposed jaw supports mounted for adjustment to and from each other, an upright disposed centrally between 100 said jaw supports, a rod for adjustably supporting said jaw supports having threaded engagement with said upright, said rod being threaded at one end, the pitch of the threads engaging the said upright being one-half that at the end of the rod, means for actuating said rod, a nut on the threaded end of said rod, springs arranged on said rod between said upright and said jaw supports coacting to hold said jaw supports yieldingly outward, jaws mounted on said jaw supports, and means for actuating said jaws. 105

21. In a structure of the class described, the combination of opposed jaw supports mounted for adjustment to and from each 115 other, an upright disposed centrally between said jaw supports, a rod for adjustably supporting said jaw supports having threaded engagement with said upright, said rod being threaded at one end, the pitch of the threads engaging the said upright being one-half that at the end of the rod, means for 120 rotating said rod, a nut on the threaded end of said rod, jaws mounted on said jaw supports, and means for actuating said jaws.

22. In a structure of the class described, the combination of opposed jaw supports mounted for adjustment to and from each other, uprights disposed centrally between said jaw supports, rods for adjustably sup- 125

porting said jaw supports having threaded engagement with said uprights and threaded at one end, nuts on said threaded ends, means for simultaneously rotating said rods, jaws 5 rockingly mounted on said jaw supports, said jaws having jaw faces above the planes of their axial centers and opposed longitudinal recesses below their said jaw faces, a fastener holder disposed between said jaws 10 with its edges engaging said recesses therein, and vertically reciprocating spring supported centering members mounted on said uprights and with which said fastener holder is engaged when the holder is in engagement with said jaws.

28. In a structure of the class described, the combination of opposed jaw supports mounted for adjustment to and from each other, uprights disposed centrally between 20 said jaw supports, means for simultaneously adjusting said jaw supports having centering engagement with said uprights, jaws 25 rockingly mounted on said jaw supports, said jaws having jaw faces above the planes of their axial centers and opposed longi-

tudinal recesses below their said jaw faces, a fastener holder disposed between said jaws with its edges engaging said recesses therein, and vertically reciprocating spring supported centering members mounted on said 30 uprights and with which said fastener holder is engaged when the holder is in engagement with said jaws.

24. In a structure of the class described, the combination of opposed jaw supports 35 mounted for adjustment to and from each other, uprights disposed centrally between said jaw supports, means for simultaneously adjusting said jaw supports having centering engagement with said uprights, jaws 40 mounted on said jaw supports, a fastener holder disposed between said jaws, and vertically reciprocating spring supported centering members mounted on said uprights and with which said fastener holder is en- 45 gaged.

In witness whereof I have hereunto set my hand.

JAMES K. DIAMOND.
